UNITED STATES PATENT OFFICE.

ROBERT KIESERLING, OF ALTONA, GERMANY.

CEMENT PAVING.

No. 892,377.

Specification of Letters Patent.

Patented June 30, 1908.

Original application filed June 2, 1905, Serial No. 263,398. Divided and this application filed July 7, 1906. Serial No. 325,153.

To all whom it may concern:

Be it known that I, ROBERT KIESERLING, a subject of the King of Prussia, and a resident of Altona, (Elbe,) Germany, have invented an Improvement in Cement Paving, of which the following is a full, clear, and exact description.

My invention relates to improvements in cement paving, this application being a division of the application filed by me on the 2nd day of June, 1905, Serial No. 263,398, for improvements in cement paving, and for which a patent was granted to me Dec. 25, 1906, No. 839,600.

15 According to my present invention I embed in a layer of concrete or cement, which may be upon a second such layer, gutters of U or V section; and I fill these gutters with some elastic substance, such as tar, mastic-cement, or the like. From the walls of the gutter project lugs, which are surrounded by the concrete, whereby the gutters are firmly held in place in the material.

The purpose of my invention is to simplify 25 and cheapen the construction shown in the patent above referred to.

My invention is illustrated in the accompanying drawings, in which

Figure 1 is a plan, showing a portion of a 30 street paved according to this invention. Fig. 2 is a cross section of a portion of the construction shown in Fig. 1 drawn to a larger scale. Fig. 3 is a side elevation of a gutter section as shown in Fig. 2.

35 The pavement consists of two superposed concrete layers *a* *b*. In the upper layer *a* there is embedded a metal gutter *c*, which may either rest with its base upon the surface of the lower concrete layer *b*, or may 40 terminate at some distance above this layer *b*, so as to leave a layer of concrete between it and the latter, as shown in Fig. 2. *d* are lugs, stamped out of the walls of the gutter *c* and bent over outwardly. These lugs are 45 naturally firmly embedded in the concrete *a* and thus afford the gutter *c* a thorough hold. After the pavement has been laid and the concrete has set, the gutter *c*, is filled with an elastic material *e*, such as tar, mastic-cement, 50 caoutchouc, so that water can not collect in

it. If desired, the gutter may be filled in this manner prior to being embedded in the concrete. In the drawings a gutter of U-section is shown, but as already remarked, a V or any other suitable section may be adopted. 55

The gutter as a rule will naturally not be in one continuous piece, but will consist of a number of separate lengths; and these are preferably laid directly adjacent or in close proximity to the curb *f*; and the two outer 60 gutters *g* thus formed are connected at intervals by cross gutters *h*.

The gutters *h* can consist of two lengths which meet together at the middle of the street in an obtuse angle, so that when 65 heavy carts pass over the same the stress will be met by two walls of the gutters and also by a part of the paving.

Having thus described my invention, what I claim as new and desire to secure by Letters Patent is:—

1. Cement paving for streets comprising in combination two layers of concrete, two narrow gutters provided in the upper layer near to the longitudinal edges, a number of gutters disposed transverse to said first gutters, and a filling of plastic material in all of said gutters, the gutters being of a substantially U-shaped cross-section and provided with means for anchoring the same, substantially 80 as and for the purpose set forth.

2. Cement paving for streets comprising in combination two layers of concrete, two narrow gutters provided in the top layer near to the longitudinal edges, transverse gutters 85 meeting together in an obtuse angle, and a filling of plastic material in all of said gutters, which gutters consist of resilient metal bent to a substantially U-shaped cross-section and provided with anchoring lugs, substantially as and for the purpose set forth.

3. Cement paving for streets comprising in combination two layers of concrete, gutters of resilient metal bent to a substantially U-shaped cross-section provided in the upper 95 layer and having a number of integral lugs in the side walls thereof, and a filling of plastic material provided in each of said gutters, substantially as and for the purpose set forth.

4. Cement paving for streets, comprising 100

layers of cement two narrow longitudinal gutters and transverse gutters embedded in the upper layer of cement, the gutters being approximately U-shape and provided with 5 integral curved lugs on their side walls, and a filling of plastic material in the gutters.

In witness whereof I have hereunto signed

my name this 23rd day of June 1906, in the presence of two subscribing witnesses.

ROBERT KIESERLING.
